UNITED STATES PATENT OFFICE.

WILLIAM J. PATTERSON, OF PITTSBURG, PENNSYLVANIA, ASSIGNOR TO HEYL AND PATTERSON, OF PITTSBURG, PENNSYLVANIA, A COPARTNERSHIP.

LADLE-TILTING DEVICE.

SPECIFICATION forming part of Letters Patent No. 761,393, dated May 31, 1904.

Application filed February 5, 1903. Serial No. 141,956. (No model.)

To all whom it may concern:

Be it known that I, WILLIAM J. PATTERSON, a resident of Pittsburgh, in the county of Allegheny and State of Pennsylvania, have invented a new and useful Improvement in Ladle-Tilting Devices; and I do hereby declare the following to be a full, clear, and exact description thereof.

My invention relates to a ladle-tilting device, and more especially for use in connection with pig-metal-casting apparatus in which the metal is discharged into a series of molds mounted on an endless chain, such as shown in Letters Patent of the United States No. 583,424, granted to A. M. Acklin the 25th day of May, 1897.

The object of my invention is to provide a simple form of apparatus adapted to be quickly connected up to the operating-shaft of any ordinary tilting ladle to drive said shaft and adapted to be withdrawn when not in use, so as not to interfere with the operations of the workmen about the plant.

To these ends my invention comprises, generally stated, a swinging frame having a power-driven shaft thereon and adapted to make connection with and operate the tilting mechanism of a tilting ladle.

My invention further comprises the novel features hereinafter set forth and claimed.

To enable those skilled in the art to make and use my invention, I will describe the same more fully, referring to the accompanying drawings, in which—

Figure 1 is a vertical elevation of my improved ladle-tilting device. Fig. 2 is a like view at right angles thereto. Fig. 3 is a plan view. Fig. 4 is an enlarged plan view of the driving and reversing mechanism. Fig. 5 is an enlarged sectional view of the clutch mechanism.

Like numerals indicate like parts in each of the figures.

The numeral 2 designates a building suitable for the purpose of containing the apparatus and into which the ladle-cars may be run for the purpose of pouring. The tracks 3 are laid into the building, and on said tracks

run the trucks 4 of the ladle-car carrying the tilting ladle 5. The ladle 5 is supported on 50 trunnions in the ordinary manner and is provided with the worm-wheel 6 and worm-shaft 7, all of the ordinary construction. A swinging frame 8 is suspended from the shaft 9, said frame being preferably composed of angle-bars 10, suitably connected and having the bearing-block 12 by means of which said frame is suspended from said shaft 9 and is adapted to swing thereon.

At the lower end of the swinging frame 8 6c is the bearing-block 13, mounted in guides 14 and adapted to slide therein. A shaft 16 is journaled in the bearing-block 13, said shaft having the sprocket-wheel 15 and extending out beyond the frame 8. The bearing-block 65 13 is provided with the adjusting-screw 17, whereby said bearing-block may be adjusted to take up any wear in the chain 18. A second sprocket-wheel 19 is mounted on the shaft 9 within the frame 8 and in line with the 70 sprocket-wheel 15 and over which the chain 18 passes.

At the upper end of the frame 8 are the weights 20, which aid in the swinging of the frame when it is desired to move the lower 75 end of said frame out of the way.

The shaft 21 may be driven by a suitable motor 22^a, and on said shaft are the pinions 22 23. The pinion 22 meshes with the large gear-wheel 24 on the shaft 9. The pinion 23 80 meshes with the intermediate gear-wheel 25 on shaft 26, said gear 25 meshing with the small gear-wheel 27 on shaft 9. By this arrangement of gears provision is made for reversing the direction of rotation of the shaft 85 9 and for increasing and decreasing the speed of same.

Any suitable clutch mechanism may be employed for effecting the reversal of the shaft 9, that shown consisting of the upright lever 28, connected to the sliding sleeve 29, connected by the toggles 30 to suitable clutches 31 32. These clutches, as illustrated in Fig. 5, are composed of the disks 33 and 34, the disk 34 being secured to the shaft 9 and said disks 95 being connected by the bolts 34^a. Interposed

between the disks 33 and 34 is the disk 34^b, secured to the sleeve 27^a on the gear-wheel 27, said gear-wheel being loosely mounted on said shaft. It has only been deemed necessary to illustrate in detail this clutch mechanism with reference to the gear-wheel 27, as the construction for the large gear-wheel 24 is the same. The lever 28 is attached to the endless operating-rope 35, which passes around the pulley 36, thence over pulley 37 to pulley 38, whence it passes down and around the pulley 39, near the floor of the building. This operating-rope 35 is provided with hand-buttons 40 for convenience in operating.

15 The shaft 16 is provided with the universal couplings 41 42, the outer one adapted to be connected up to the worm-shaft 7, whereby provision is made for connecting up the shaft 16 to the worm-shaft 7 in case said shafts are not in exact alinement. This shaft 16 is supported by brackets 16^a on the swinging frame 8, the outer end of said shaft carrying the coupling 42 being supported by the bracket 16^b on the ladle-frame. A shaft 16^c, supported by the bracket 16^d on the ladle-frame, acts to hold the bevel-gear 7^a into engagement with the bevel-gear 7^b on the worm-shaft 7.

20 25 30 35 40 45 50 55 60

The operation of my improved ladle-tilting device is as follows: The ladle-car is run into the casting-house on the tracks 3, and when the ladle is brought into proper position for pouring the coupling 42 is connected up to worm-shaft 7. The operator then grasps the proper hand-button 40 and pulls the operating-rope 35. This operates the clutch 32 and causes the shaft-line to be driven by pinion 22, meshing with large gear-wheel 24. The shaft 9 is rotated in the proper direction, and through the sprockets 15 19 and chain 18 the shaft 16 is also rotated. Power is thus transmitted from the swinging frame to the worm-shaft 7 to effect the tilting of the ladle. The shaft 7 continues to rotate in a steady positive manner, so as to pour the metal in an even well-controlled stream until all the metal has been poured. The operator then grasps the other hand-button and by pulling the operating-rope 35 the clutch 32 is disengaged and clutch 31 thrown into engagement. The shaft 9 is now driven by the pinion 23 and large gear 25 and pinion 27 in the opposite direction and at an increased rate of speed. This reverses the direction of rotation of worm-shaft 7 and the ladle is brought back to its normal position and that at an increased rate of speed over that of the tilting operation. In this manner the righting of the ladle is accomplished in less time and the empty ladle withdrawn and a full one brought into position for pouring and a greater amount of metal handled in a given time.

The swinging frame may be readily swung to one side when not in use, as the weighted

upper end makes it possible to swing the frame with little exertion and acts to retain it in the inclined position. When withdrawn, the swinging frame in no wise interferes with the movement of the ladle-cars or the locomotive used for transferring said cars.

70

What I claim is—

1. In ladle-tilting apparatus, the combination with a suitable tilting ladle having tilting mechanism, of a swinging frame, a power-driven shaft on said frame, and means for connecting said tilting mechanism with said shaft. 75
2. In ladle-tilting apparatus, the combination with a suitable tilting ladle having tilting mechanism, of a swinging frame, a power-driven shaft on said frame, means for connecting said tilting mechanism with said shaft, and means for driving said shaft in opposite directions. 80
3. In ladle-tilting apparatus, the combination with a suitable tilting ladle having tilting mechanism, of a swinging frame, a power-driven shaft on said frame connecting said tilting mechanism with said shaft and for driving said shaft in opposite directions at different rates of speed. 85
4. In ladle-tilting apparatus, the combination with a suitable tilting ladle having tilting mechanism, of a swinging frame, a power-driven shaft on said frame, and a universal coupling connecting between said shaft and 90 said tilting mechanism.
5. In ladle-tilting apparatus, the combination with a suitable tilting ladle having an operating-shaft, of a swinging frame, a power-driven shaft on said frame, and means for connecting said shafts. 100
6. In ladle-tilting apparatus, the combination with a suitable tilting ladle having an operating-shaft, of a swinging frame, a power-driven shaft on said frame, and a universal 105 coupling between said shafts.
7. In ladle-tilting apparatus, the combination with a suitable tilting ladle having tilting mechanism, of a shaft, a swinging frame mounted on said shaft, a shaft on said frame, connections between said shafts, means for connecting said last-named shaft to said tilting mechanism and for driving said shaft in opposite directions. 110
8. In ladle-tilting apparatus, the combination with a suitable tilting ladle having an operating-shaft, of a shaft, a swinging frame mounted thereon, a sprocket-wheel on said shaft, a shaft on said frame, a sprocket-wheel on said shaft, a driving-chain, mechanism for driving said first-named shaft in opposite directions, and means for connecting said shaft on said frame to said operating-shaft. 115
9. In ladle-tilting apparatus, the combination with a suitable tilting ladle having an operating-shaft, of a power-driven shaft, a counter-shaft, reversing mechanism for changing 120 direction of rotation of said counter-shaft, a

swinging frame on said counter-shaft, a shaft on said frame, connections between said last-named shaft and said counter-shaft, and means for connecting said shaft on said frame to 5 said operating-shaft.

10. In ladle-tilting apparatus, the combination with a suitable tilting ladle having an operating-shaft, of a power-driven shaft, a counter-shaft, a swinging frame on said counter-shaft, a pinion on said power-shaft, a large gear-wheel on said counter-shaft with which 10 said pinion meshes, a second pinion on said power-shaft, an interposed gear-wheel with which said pinion meshes, a pinion on said 15 counter-shaft meshing with said interposed gear, clutch mechanism for engaging said large gear and said pinion on said counter-shaft, a shaft on said swinging frame, connections between said shaft and said counter-shaft, and means for connecting said shaft to 20 said operating-shaft.

11. In ladle-tilting apparatus, the combination with a suitable tilting ladle having an operating-shaft, of a power-shaft, a counter-shaft, connections between said shafts for 25 driving said counter-shaft in opposite directions, clutch mechanism on said counter-shaft, an endless rope attached to said clutch mechanism, pulleys over which said rope passes, a 30 swinging frame on said counter-shaft, a shaft on said frame, connections between said shaft

and said counter-shaft, and means for connecting said shaft to said operating-shaft.

12. In ladle-tilting apparatus, the combination with a suitable tilting ladle having an operating-shaft, of a power-shaft, a counter-shaft, a swinging frame on said counter-shaft, connections between said shafts for driving 35 said counter-shaft in opposite directions, clutch mechanism on said counter-shaft, a lever on said clutch mechanism, an endless rope attached to said lever, pulleys over which said rope passes, a swinging frame on said counter-shaft, a shaft on said frame, connections between said shaft and said counter-shaft, and 40 means for connecting said shaft to said operating mechanism.

13. In ladle-tilting apparatus, a counterbalanced swinging frame adapted to be brought into operative position with reference to said 45 ladle to tilt same, and adapted to be swung to one side when not in use.

14. In ladle-tilting apparatus, a swinging frame weighted at its upper end and adapted to be brought into operative position with reference to said ladle to tilt same.

In testimony whereof I, the said WILLIAM J. PATTERSON, have hereunto set my hand.

WILLIAM J. PATTERSON.
